UNITED STATES PATENT OFFICE

HERMAN HOLLERITH, JR., OF RIVERTON, NEW JERSEY, ASSIGNOR, BY MESNE ASSIGNMENTS, TO RADIO CORPORATION OF AMERICA, OF NEW YORK, N. Y., A CORPORATION OF DELAWARE

MOUNTING FOR RADIO ANTENNAE

Application filed February 17, 1926. Serial No. 88,887.

This invention relates to coil or loop antennae for use in radio signaling, and more particularly to means for mounting an antenna of this character.

5 In order to receive the strongest signal, or to pick up the maximum amount of radiant signal energy, an antenna of this type must be so mounted that it can be moved to bring the vertical plane of the coil into a plane 55 through the transmitting station being received. For the most part, the desired adjustment of coil antennae has heretofore been secured by providing mountings for the same which are separate and independent of the 10 mountings for the radio instruments with which said antennae are associated. The antenna mounting is usually seated on top of the cabinet for the radio instrument where it not only presents an unpleasing appearance, due to the construction necessarily employed, but is likely to be overturned and 15 damaged.

An object of the present invention is to provide, in combination with a supporting 20 member such as a radio receiving instrument cabinet or a combined radio and talking machine cabinet, a coil or loop antenna which may be readily adjusted to a position to secure maximum signal reception.

25 Another object of this invention is to provide novel means for mounting a coil or loop antenna on a cabinet of the above character.

A further object is to provide, in combination with a cabinet, a novel mounting for 30 a coil or loop which is so constructed that said coil or loop, when not in use, may be disposed against the bottom of the supporting cabinet in order that the antenna will 35 be out of view and will not detract from the appearance of the cabinet.

A still further object is to provide a novel cabinet mounting for a coil or loop antenna which is so constructed that the latter may 40 be moved about a vertical axis into any desired vertical plane, and may also be swung about a horizontal axis for disposition adjacent the bottom of the cabinet. These and other objects will appear more fully hereinafter.

The invention will be readily understood by reference to the accompanying drawings which illustrate one embodiment of the present invention. It is to be expressly understood, however, that these drawings are for 55 the purpose of illustration only and are not designed as a definition of the limits of the invention, reference being had to the appended claims for this purpose.

In the drawings, wherein like reference 60 characters refer to like parts throughout the several views,

Fig. 1 is a perspective view illustrating one manner in which a loop antenna may be mounted in accordance with the present invention, on the lower surface of a cabinet such as a combined talking machine and 65 radio cabinet, portions of the latter being broken away;

Fig. 2 is a perspective view illustrating 70 one manner in which the antenna may be housed when not in use;

Fig. 3 is a perspective view illustrating the antenna in a position at 90° from the 75 positions shown in Figs. 1 and 2 respectively; and

Fig. 4 is a sectional side elevation, somewhat enlarged, illustrating the details of one type of mounting which may be employed.

80 Referring to the drawings, the reference character 1 represents a cabinet, such as a radio receiving instrument cabinet, or for a combined talking machine and radio receiving instrument cabinet of any suitable type, 85 which is provided with a bottom or closure member 2, a suitable number of supporting legs 3, and bracing members 4 and 5 for said legs. Suitably attached to the bottom 2 at a convenient point, is a bracket member 6 which 90 is preferably bent and shaped into such form as to comprise two triangular-shaped side portions 6a and 6b which are substantially at right angles one with the other. As shown, the bracket 6 may be provided with a suitable 95 number of integrally formed ears 6c for attaching the bracket to the cabinet bottom 2. A pair of vertically aligned ears 7, which are preferably formed integral with the stationary bracket 6, are provided with 100

registering openings through which passes a pivot member 8. As shown, this pivot member may be constituted by a flat-headed bolt that is secured in position by means of a split pin 9. Attached to the vertically disposed pivot member 8, intermediate the ears 7, is a substantially triangular-shaped bracket member 10, the connection between said member 10 and pivot member 8 preferably being by means of a pair of vertically alined ears 11 which, as shown, are formed integrally with the member 10.

A second pivot member 12 is mounted in the swinging bracket 10 in a horizontal position, as by means of a pair of horizontally disposed ears 13. Secured in any suitable manner to the pivot pin 12, as by means of a pair of upstanding ears 14, is a plate 15 which is attached, as by means of screws, to a frame 16 which may be of any suitable outline but which is illustrated in the drawings as being substantially rectangular. Wound around the frame 16 or, if desired, enclosed in a housing constituted by said frame 16, is a coil or a loop antenna consisting of a pluralitiy of turns of suitable wire 17. The electrical characteristics of the coil constituted by the wire 17, such as inductance and resistance, constitutes no part of the present invention.

The opposite ends of the coil are suitably secured to terminal posts 18 mounted at a convenient point on the frame 16 and a pair of terminals 19 lead from said posts through an opening, or openings, 20 in the closure member 2, to the radio instrument housed in the cabinet 1.

Secured to one side of the frame 16, and preferably adjacent the corner of said frame opposite that to which the plate 15 is secured, is a bracket 21 that is provided with an inwardly extending pivot pin 22, which latter preferably lies in an extension of the longitudinal axis of the horizontally disposed pivot pin 12. To the bottom 2 of the cabinet there is attached an angular-shaped supporting member 23 which is adapted to receive and detachably retain the pivot pin 22.

Suitable means are preferably provided for yieldingly retaining the frame 16 against the bottom 2 of the cabinet. In the form shown, this means, which coacts with the supporting brackets described above, is constituted by a yielding spring catch 24 which is adapted to engage one end of the frame 16. If desired, a wear plate 25 may be secured to the frame 16 in such position as to prevent the catch 24 from having direct engagement with the said frame.

When the radio receiving instrument with which the antenna is associated is not in use, the latter is preferably in the position shown in Fig. 2. In this position the frame 16 is yieldingly supported at one end by the spring catch 24 and at its opposite end is positively supported by pivot pin 22 coacting with sup-

porting member 23, and also by means of the universal mounting constituted by brackets 6 and 10, plate 15 and pivot pins 8 and 12. When it is desired to use the radio instrument, the coil 17 and consequently the frame 16, is 70 swung about the horizontal axis constituted by pivot pins 12 and 22, to the position shown in Fig. 3, i. e., the frame 16 is swung through 90° from the horizontal position shown in Fig. 2 to the vertical position shown in Fig. 3, 75 a slight pressure only being necessary to disengage the frame from the spring catch 24.

If the cabinet 1 is so placed that the vertical plane of the coil 17 does not pass through the transmitting station it is desired to receive, the frame 16 may be swung about the vertical axis of the pivot pin 8 to the desired position. Only a slight pressure is required to swing the frame 16 about the pivot 8 since pin 22 will readily slide out of engagement with the supporting portion of member 23. The relative proportions of the frame 16 and legs 3 of the cabinet 1 are such that frame 16 has free movement between the bottom 2 and the bracing members 4, 5 in a vertical plane and consequently free movement for swinging about the horizontal axis of the pins 22 and 12.

There is thus provided a coil antenna in combination with a supporting cabinet, the antenna being so mounted that the same may be swung about a horizontal axis for disposition against the bottom of the cabinet when the antenna is not in use and which may be readily moved to a vertical position and 100 swung about a vertical axis into any desired vertical plane. When swung into the horizontal position for disposition against the bottom of the cabinet, the antenna is hid from view and does not detract from the pleasing appearance of the cabinet. The device is simple in operation and inexpensive to manufacture. The likelihood of damage to the antenna resulting from the use of a separate mounting for the same is avoided.

While one embodiment of the invention has been illustrated and described with considerable detail, it is to be expressly understood that the invention is not limited thereto. For example, the frame 16 may assume various shapes as desired, and the members 21, 22, 23 may or may not be employed. Various other changes may be made within the limits of the appended claims.

What is claimed is:

1. In combination, a cabinet, a coil antenna, and means for securing said coil antenna to the bottom of said cabinet, said means including a member permitting movement of the antenna about a vertical axis into a desired vertical plane and a member permitting movement of said antenna about a horizontal axis for disposition against the bottom of the cabinet.

2. In combination, a cabinet, a bracket se-

cured thereto, a coil antenna, means including horizontal and vertical pivot members for securing the antenna to said bracket, and means for yieldingly securing said antenna in horizontal position beneath said cabinet.

5. In combination, a cabinet, a frame, an antenna carried by said frame, means permitting movement of said frame about horizontal and vertical axes for connecting the frame to said cabinet, and means for yieldingly maintaining the frame in a substantially horizontal position adjacent the bottom of said cabinet.

10. 3. In combination, a cabinet, a bracket secured to the bottom of the cabinet, a second bracket pivotally secured to said first-named bracket, a loop antenna pivotally secured to said second bracket, and means carried by the cabinet and adapted to engage the loop antenna to maintain the latter in a substantially horizontal plane beneath said cabinet.

15. 4. In combination, a cabinet, a bracket secured to the bottom of said cabinet, a vertically disposed member carried by said bracket, a second bracket secured to said member, a horizontally disposed member carried by said second bracket, a loop antenna, means for securing the said antenna to said horizontal member, and means including a resilient member carried by the cabinet for maintaining said antenna in a substantially horizontal plane beneath said cabinet.

20. 5. In combination, a cabinet having a horizontally disposed bottom portion, supporting means for the cabinet, a frame, a loop antenna carried by the frame, pivot means for securing said frame to the bottom portion of said cabinet, said pivot means permitting movement of the antenna about vertical and horizontal axes, and additional means on said frame adapted to pivotally engage said cabinet when said frame is moved about its horizontal axis.

25. 6. In combination, a talking machine cabinet, supporting legs therefor, a substantially rectangular frame, an antenna carried by the frame, means secured to said frame adjacent an upper corner thereof and to said cabinet, in substantially the same plane as the upper ends of said legs, for pivotally connecting said antenna to the cabinet, said means permitting pivotal movement of the antenna about vertical and horizontal axes, and a pivot member adjacent the opposite upper corner of said frame adapted to pivotally engage said cabinet when the frame is moved about its horizontal axis.

30. In testimony whereof I have signed this specification.

HERMAN HOLLERITH, JR.
